UNITED STATES PATENT OFFICE.

FREDERICK W. WILKES, OF SPARKHILL, BIRMINGHAM, ENGLAND.

EMERGENCY HANDLE FOR DOMESTIC RECEPTACLES.

Application filed March 7, 1922. Serial No. 541,632.

To all whom it may concern:

Be it known that I, FREDERICK WARREN WILKES, a subject of the King of Great Britain, residing at 61 Adria Road, Sparkhill, Birmingham, in the county of Warwick, England, have invented certain new and useful Improvements Relating to an Emergency Handle for Domestic Receptacles; and I do hereby declare the following to be a full, clear, and exact description of the same.

This invention relates to domestic receptacles such as cups or jugs and has for its object to provide an emergency handle which can be applied to such receptacles in the event of the usual handle being broken.

A device according to the present invention comprises a handle shaped member made of suitable material having at one end a hook portion adapted to engage over the edge of the receptacle and having at its other end an abutment portion adapted to engage against the side of the receptacle.

Referring to the drawings:-

Figure 1 is a perspective view showing the device in position on a cup.

Figure 2 is an elevation of the device.

In the construction illustrated in Figures 1 and 2, the detachable handle is made from sheet metal pressed out from a single blank, the upper end being formed as a resilient hook 1 having two limbs, one of which consists of two spring tongues 2 adapted to engage upon the inner side of the receptacle 10 whilst the other 3 is disposed upon the exterior of the upper part of the receptacle 10.

The middle portion 4 of the device is made of the usual handle shape or loop and is pressed into a curve in cross section.

The lower end or shoulder 5 of the device is adapted to abut against the side of the exterior of the receptacle 10 and is provided with the rubber band 6 which is adapted to press against the receptacle 10.

This rubber band may be replaced by a rubber or other pad secured to the device by any suitable means such as by pressing out small tongues of metal to engage with the pad.

What I claim then is:-

1. An emergency handle for domestic receptacles, having a bow shaped portion for engagement by the fingers; a hook portion at one end of said bow shaped portion, having two spaced fluted limbs to engage over the edge of the receptacle; a shoulder on the other end of the bow shaped portion to bear against the side of the receptacle; and an elastic band disposed around said shoulder to prevent accidental slipping movement thereof on the side of the receptacle; all arranged so that a handle of a standard size can be applied to and gives a secure three point grip upon receptacles of greatly varying size.

2. An emergency handle for domestic receptacles comprising a sheet metal member, having a fluted bow shaped central portion adapted for engagement by the fingers; a shoulder at one end thereof adapted to fit against the side of the receptacle; a straight strut portion intermediate the said bow shaped portion and the shoulder to hold the latter against the side of the receptacle; a U shaped portion at the opposite end of the bow shaped portion; two laterally extending fluted portions on the outer limb of said U shaped portion, disposed one on each side of the handle; two fluted extremities on this end, extending parallel to the arms of the U shaped portion and spaced apart laterally one on each side of the handle opposite the fluted portions on the U shaped portion; and an elastic band disposed around said shoulder to prevent the shoulder from slipping on the side of the receptacle; all so arranged that the two fluted extremities and the laterally extending fluted portions engage with opposite sides of the receptacle in two spaced positions, and the shoulder engages with a third spaced point, whereby a standard handle gives a secure three point grip upon receptacles of greatly varying size.

In witness whereof I affix my signature.

F. W. WILKES.
